UNITED STATES PATENT OFFICE.

FRANK P. NOE AND SETH M. GOODER, OF CHICAGO, ILLINOIS.

JACK.

Original application filed January 13, 1926, Serial No. 80,905. Divided and this application filed July 30, 1926. Serial No. 125,901.

The present invention relates to a jack which, while adapted for other uses, may be employed with particular advantage in the construction of concrete walls within deep trenches.

The manner of using the jack in the construction of concrete walls is set forth in our application Serial No. 80,905 filed January 13, 1926, of which application this application is a division.

The various features of novelty whereby our invention is characterized will herein-after be pointed out with particularity in the claims; but, for a full understanding of our invention and of its objects and advantages, reference may be had to the following detailed description taken in connection with the accompanying drawing, wherein:

Figure 1 is a top plan view of a pair of jacks associated with a beam that serves as a base for both and as a spacing means therefor; and Fig. 2 is a section taken on approximately line 2—2 of Fig. 1.

The two jacks illustrated are alike and the description of one will suffice for both. The body 1 of the jack is made of a piece of thin-walled steel pipe. Set into one end of the pipe is a head 2 that is preferably provided with a lug 3 that enters a notch 4 cut into the end of the pipe, to prevent the head from turning. A jack screw 5 passes through the head and is provided on its outer end with suitable means by which it may be turned. In the arrangement shown, the screw has on the outer end a ball 6 through which are bored holes 7 and 8 to receive a rod or lever. A foot 9 is swiveled to the ball and is adapted to engage with one of the members between which the jack is placed. The jack screw is much shorter than the body of the jack, permitting the base end of the body to be filled with concrete 10.

In using the jacks in groups, a plurality of them are set into the channel of a chan-

nel beam 11 that will serve as a common base or as a waler extending transversely across the lagging in a trench, where the jacks are employed to sustain the sides of the trench. It is preferred that the jacks be interlocked with the beam to permit them to be easily set up in proper spaced relation to each other and be held there. In the arrangement shown, the beam has discs 12 riveted or otherwise secured to the inner side of the web; these discs being of the same diameter as the internal diameter of the body member of the jack. The concrete within the jack terminates a short distance from the end of the latter so as to leave room for the entry of one of the discs.

While we have illustrated and described with particularity only a single preferred form of our invention, we do not desire to be limited to the exact structural details thus illustrated and described; but intend to cover all forms and arrangements which come within the definitions of our invention constituting the appended claims.

We claim:

1. A jack device comprising a body member in the form of a long thin walled pipe having one end filled with concrete, a head at the other end of the pipe, and a jack screw extending through said head into the free space in the pipe.

2. A device for use in the construction of walls in trenches comprising a beam member, and a plurality of jacks spaced along said beam member and projecting laterally therefrom in parallel relation to each other, said jacks having body members in the form of thin walled pipes filled with concrete at the ends adjacent to the beam.

In testimony whereof, we sign this specification.

FRANK P. NOE.
SETH M. GOODER.
